US00D523758S

(12) United States Design Patent (10) Patent No.: US D523,758 S
(45) Date of Patent: * Jun. 27, 2006

(54) FLEXIBLE PACKAGING

(75) Inventor: Eric Risgalla, Geneva (CH)

(73) Assignee: Pakerman S.A., Geneva (CH)

() Term: 14 Years

(21) Appl. No.: 29/203,443

(22) Filed: Apr. 14, 2004

(30) Foreign Application Priority Data

Oct. 15, 2003 (CH) 130092

(51) LOC (8) Cl. 09-05

(52) U.S. Cl. D9/707

(58) Field of Classification Search D9/702-710,
D9/713-714, 720, 722, 711; D28/118, 207,

D28/224; 383/61.2, 104, 200
